UNITED STATES PATENT OFFICE

153,896

DESIGN FOR A LOCOMOTIVE BODY

Ray Patten, Norwalk, Conn., assignor to General
Electric Company, a corporation of New York

Application August 16, 1946, Serial No. 132,587

Term of patent 3½ years

(Cl. D66—1)

To all whom it may concern:

Be it known that I, Ray Patten, a citizen of the United States, residing at Norwalk, in the county of Fairfield, State of Connecticut, have invented a new, original, and ornamental Design for a Locomotive Body, of which the following is a specification, reference being had to the accompanying drawing, forming a part thereof.

In the drawing, Fig. 1 is a side elevational view; Fig. 2 is a plan view; Fig. 3 is a perspective view; and Fig. 4 is a front elevational view of a locomotive body embodying my new design. The other side is the same as that shown.

I claim:

The ornamental design for a locomotive body, substantially as shown and described.

RAY PATTEN.
